(57) **CLAIM**

The ornamental design for a sport object embedded in wall, as shown and described.

DESCRIPTION

FIG. 1 is a perspective view of a sport object embedded in wall;

FIG. 2 is a front elevational view of the sport object embedded in wall shown in FIG. 1;

FIG. 3 is a top view the sport object embedded in wall shown in FIG. 1;

FIG. 4 is a bottom view the sport object embedded in wall shown in FIG. 1;

FIG. 5 is a left side view the sport object embedded in wall shown in FIG. 1; and,

FIG. 6 is a right side view the sport object embedded in wall shown in FIG. 1.

The lines making up the perimeter of the article are shown broken away to indicate that they have no particular length beyond what is shown.

1 Claim, 4 Drawing Sheets
